US0D1079606S

(12) **United States Design Patent** (10) **Patent No.:** **US D1,079,606 S**
(45) **Date of Patent:** **** Jun. 17, 2025**

(54) **ENERGY STORAGE DEVICE**

(71) Applicant: **Anker Innovations Technology Co., Ltd.**, Changsha (CN)

(72) Inventor: **Zhipeng Ke**, Shenzhen (CN)

(73) Assignee: **Anker Innovations Technology Co., Ltd.**, Changsha (CN)

(**) Term: **15 Years**

(21) Appl. No.: **29/967,647**

(22) Filed: **Oct. 11, 2024**

(30) **Foreign Application Priority Data**

Apr. 12, 2024 (CN) 202430204973.1

(51) **LOC (15) Cl.** **13-02**

(52) **U.S. Cl.**

USPC **D13/108**

(58) **Field of Classification Search**

USPC D13/103, 104, 105, 107, 108, 109, 119,

D13/120, 146, 149, 154, 173, 199

(57) **CLAIM**

The ornamental design for an energy storage device as shown and described.

DESCRIPTION

FIG. 1 is a front top perspective view of an energy storage device showing my new design;

FIG. 2 is a rear bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines depict portions of the energy storage device that form no part of the claimed design.

1 Claim, 8 Drawing Sheets
